UNITED STATES PATENT OFFICE.

JOHN C. DALLAM, OF SCHENECTADY, NEW YORK, ASSIGNOR TO GENERAL ELECTRIC COMPANY, A CORPORATION OF NEW YORK.

LAMP-SOCKET.

No. 829,850.

Specification of Letters Patent.

Patented Aug. 28, 1906.

Application filed August 12, 1905. Serial No. 273,891.

To all whom it may concern:

Be it known that I, JOHN C. DALLAM, a citizen of the United States, residing at Schenectady, county of Schenectady, and State of New York, have invented certain new and useful Improvements in Lamp-Sockets, of which the following is a specification.

This invention relates to electric lighting; and its object is to provide a cheap and simple socket for an incandescent electric lamp, especially intended for use in decorative installations where a large number of lamps are controlled by a single switch, so that no key is necessary in the individual lamp-sockets. In such installations the sockets are strung along the line-wires, which are bared where they pass through the sockets to make good connection with the socket-contacts.

The present invention aims to reduce the labor and material consumed in making such a socket, and the features of novelty are hereinafter fully set forth, and particularly pointed out in the claims.

In the accompanying drawings, Figure 1 is a side elevation of a complete socket embodying my invention. Fig. 2 is a longitudinal section of the same on the line 22, Fig. 3. Fig. 3 is an end view with the cap removed; and Fig. 4 is a longitudinal section on the line 44, Fig. 3, showing a modified form of cap.

The socket comprises a cup-shaped body 1, of insulating material, preferably molded porcelain. It is preferably circular in cross-section and surrounds a screw-threaded metallic shell 2, which has flanges 3, through which pass fastening-screws 45. The screw 4 meshes with a nut 6, held in a polygonal recess 7 in the top of said body 1, the recess being filled with pitch- or cement, if desired.

The screw 5 enters a tapped hole in one end of a metallic strip 8, lying in a recess 9 in the top of said body and intersecting one of two parallel grooves 10 11 formed across the top of said body on either side of the center thereof.

A binding-screw 12 passes through that end of the strip 8 which lies in the groove 10, the head of said screw being partly received in a side recess 13. The screw-threaded shell 2 is notched at each side to fit over a rib 14, extending across the inner end of the body 1. A long screw 15 passes through this rib, its head being preferably countersunk therein and provided with a thin metal washer 16. The screw also passes through a metal strip 17,

placed across the groove 11, with its ends received in lateral recesses 18 19, extending therefrom. This strip has a binding-screw 20. The long screw 15 projects beyond the end of the body 1 into a nut 21, secured in a cap 22, of molded porcelain or the like, which is preferably circular and has a flange 23 fitting over the edge of said body. As the screw 15 is in the center of the body, the cap can be screwed on by simply engaging the nut with the screw and then rotating said cap. The nut is located in a countersunk hole 24, where it is secured by cement 25. When the socket is to be suspended by a cord, the cap is made as shown in Figs. 1 and 2, with a knob 26, having a transverse hole 27, through which the cord can be run; but if the socket is to be fastened to a ceiling or wall or other stationary support it is better to use the cap shown in Fig. 4, which has a flat base extending beyond the body 1 and provided with holes 28 for fastening-screws.

In using this socket the cap is unscrewed and the two line-wires are laid in the grooves 10 11, their insulation having been removed at these points to permit the binding-screws 12 20 to make good electrical contact with them. This puts the screw-threaded shell 2 in circuit with one line-wire and the central screw 15 in circuit with the other line-wire in readiness to make contact with the lamp-terminals when the lamp is screwed into the socket. The cap is then screwed on again, and the socket is ready to be hung up or fastened to its support.

What I claim as new, and desire to secure by Letters Patent of the United States, is—

1. An electric-lamp socket, comprising a cup-shaped body and a cap therefor, a shell-contact secured in said body, a center contact fixed in the center of said body and having a threaded end projecting beyond said body, and a nut centrally fixed in said cap and cooperating with said center contact, whereby said parts can be secured together by rotating one with reference to the other.

2. An electric-lamp socket, comprising a cup-shaped body having parallel grooves across its end and recesses extending from each side of each groove, metal strips reaching across said grooves with their ends in the side recesses, binding-screws in said strips, a center-contact screw passing through the end of said body and one of said strips, to

which it is secured and beyond which it projects, a shell-contact in said body and connected with the other strip, and a cap having a central nut to engage with the projecting end of the center-contact screw.

3. An electric-lamp socket, comprising a cup-shaped body circular in cross-section and having parallel grooves across its end and side recesses extending therefrom, metal strips placed across said grooves and in said recesses, binding-screws in said strips, a shell-contact in said body connected with one of said strips, a fixed center-contact screw pass-

ing through the end of said body and secured to the other strip, a cap having a circular flange fitting over the edge of said body, and provided with a central hole, and a nut cemented in said hole and meshing with said contact-screw.

In witness whereof I have hereunto set my hand this 10th day of August, 1905.

JOHN C. DALLAM.
